(57) **CLAIM**

The ornamental design for a skin toning device, as shown and described.

DESCRIPTION

FIG. 1 is a front perspective view of the skin toning device of the present invention;

FIG. 2 is a rear perspective view of the skin toning device shown in FIG. 1;

FIG. 3 is a front elevational view of the skin toning device shown in FIG. 1;

FIG. 4 is a rear elevational view of the skin toning device shown in FIG. 1;

FIG. 5 is a left side elevational view of the skin toning device shown in FIG. 1, the right side view being a mirror image of the illustrated view;

FIG. 6 is a top plan view of the skin toning device shown in FIG. 1; and,

FIG. 7 is a bottom plan view of the skin toning device shown in FIG. 1.

In the drawings, the dashed broken lines represent portions of the article that form no part of the claimed design. In the drawings, the dot-dash broken lines define the bounds of the claimed design and form no part thereof.
